UNITED STATES PATENT OFFICE.

HERBERT O. TIBBITS, OF CLEVELAND, OHIO.

DEVICE FOR CREEASING CARDBOARD AND THE LIKE.

1,367,675.

Specification of Letters Patent.

Patented Feb. 8, 1921.

Application filed August 25, 1919. Serial No. 319,713.

To all whom it may concern:

Be it known that I, HERBERT O. TIBBITS, a citizen of the United States, and a resident of Cleveland, county of Cuyahoga, and 5 State of Ohio, have invented a new and useful Improvement in Devices for Creasing Cardboard and the like, of which the following is a specification, the principle of the invention being herein explained and the 10 best mode in which I have contemplated applying that principle, so as to distinguish it from other inventions.

The present apparatus relates to apparatus suitable for use on a press for creasing cardboard coverstock and like material for folders, booklet covers and similar articles. The apparatus is designed to be mounted in a job press and is so arranged that cardboard folders may be quickly and 15 readily creased and made ready for folding. Provision is made for adjusting the apparatus so that creases of any suitable width may be made and so that the creases may be made at any desired distance apart. To 20 the accomplishment of the foregoing and related ends, said invention, then, consists of the means hereinafter fully described and particularly pointed out in the claims.

The annexed drawings and the following 30 description set forth in detail certain mechanism embodying the invention, such disclosed means constituting, however, but one of various mechanical forms in which the principle of the invention may be used.

In said annexed drawings:

Figure 1 is a plan view of a chase carrying the male die members and adjusting mechanism; Fig. 2 is a plan view of the lower plate and female die members; Fig. 40 3 is a section on the line 3—3 Fig. 2; Fig. 4 is a side elevation of the creasing blade; Fig. 5 is a section on the line 5—5 Fig. 1; Fig. 6 is a section on line 6—6, Fig. 1, and also showing a broken section through the 45 plate showing the relative position of the same just prior to contact; Fig. 7 is an enlarged view showing one set of dies in contact; and Fig. 8 is a section through a folded joint in the cardboard.

The apparatus consists of a chase or frame 50 1 adapted to be attached to the bed of a press. At the sides of the chase two straps 2 are mounted. These straps have offset ends 3 which are bolted or otherwise secured 55 to the chase, the center portion of the strap standing away from and parallel to side

frame members. Mounted through the offset portion of the straps are two shafts 5 which have bevel gears 6 thereon. Carried through the straps are two pairs of worm 60 screws 7 and 8 carrying bevel gears 9 at their outer ends, which mesh with the gears 6. At the center of the chase is a bar 10 in which the screws 7 and 8 are mounted, the ends of each pair of shafts abutting as best 65 seen in Fig. 6.

Mounted on the worm screws 7 and 8 are knurled rollers 11 and 12, the rollers 11 being secured to the ends of the screws 7 by set screws 13, while the rollers 12 are tapped 70 and engage with the threads 14 of the worm screws. Both pairs of shafts are to be rotated by means of the rollers 11, the rollers 12 being adapted to be screwed tight against the bar 10 to lock the screws after they have 75 been turned to adjust the dies.

The male dies of which two are shown, are composed of two clamping members 15 which have extending ends or fingers 16 which slide over the end members of the 80 chase. These two members are provided with two aligned apertures 17, the aperture in one of the members being threaded and adapted to engage with the threaded shafts so as to move along the same. To hold the 85 clamping members together they are provided with apertures 18 in which set screws 19 are mounted. Between the two members is mounted the creasing blade 21 which has slots 22 to receive the set screws 19 and 90 other slots 23 for receiving the shafts 7 and 8.

The creasing blade may extend beyond the two clamping members any desired distance as shown in Fig. 7. It will be understood 95 that several blades will be used, the blades being changed for extremes in thicknesses of stock used. The blade may be readily changed or adjusted between the members for creases of different width or depth.

A plate 25 is used which will be suitably attached to the movable press bed and this plate is provided with a sheet 26 of cardboard or like material. The female die members are attached to this plate over the 105 cardboard as shown in Fig. 6. These female members have a hook shaped end 28 and two flat strips 29 which have rounded edges 30. The front end is provided with a set screw 31 adapted to engage the edge of the plate 110 to hold the die members in position.

Along the top of the chase is a scale 32

attached to one of the male dies so that the position of the male dies may be quickly and accurately determined. After these have been set the position of the female dies is determined and a line drawn on the cardboard. The dies are then hooked over the plate and lined up, with the slot between the two strips in alinement with the lines on the cardboard and the creasing 10 blade.

In creasing a cardboard 40 after the position of the dies are determined, the cardboard sheet is placed in position on the plate over the female dies and positioned 15 in the usual manner by gage pins or the like and the plate and bed are then moved into engagement with the male dies until the dies are in the position illustrated in Fig. 7. When the board 40 is removed it 20 is folded and takes the form shown in Fig. 8.

By means of the adjusting mechanism the creasing blades may be quickly positioned in proper relation. In this type of work, the number of folders of any one size which 25 are creased at one time is usually small and consequently the ease of positioning the blades and the rapidity of changing the blades is of importance. The female members are of a width suitable to the stock used and are changed for extreme differences 30 on thickness of stock, several widths of dies being usually available.

Other modes of applying the principle of my invention may be employed instead of 35 the one explained, change being made as regards the mechanism herein disclosed, provided the means stated by any of the following claims or the equivalent of such stated means be employed.

40 I therefore particularly point out and distinctly claim as my invention:

1. In a creasing attachment for job presses, the combination of an open rectangular frame adapted to be removably secured to one of the two relatively movable 45 press parts, creasing blades movably mounted in said frame, a plate adapted to be removably secured to the other relatively movable press part, and female die strips 50 adjustably and removably mounted on said plate and adapted to coöperate with said creasing blades upon operation of said press.

2. In a creasing attachment for job 55 presses, the combination of an open rectangular frame adapted to be removably secured to one of the two relatively movable press parts, creasing blades movably mounted in said frame, means carried by 60 said frame for moving said blades, a plate adapted to be removably secured to the other relatively movable press part, and female die strips adjustably and removably mounted on said plate and adapted to co-

operate with said creasing blades upon operation of said press. 65

3. In a creasing attachment for job presses, the combination of an open rectangular frame adapted to be removably secured to one of the two relatively movable 70 press parts, creasing blades movably mounted in said frame, means carried in said frame for moving said blades in parallel relation, means for locking said blades in position, a plate adapted to be removably 75 secured to the other relatively movable press part, and female die strips adjustably and removably mounted on said plate and adapted to coöperate with said creasing blades upon operation of said press. 80

4. In a creasing attachment for job presses, the combination of an open rectangular frame adapted to be removably secured to one of the two relatively movable 85 press parts, creasing blades movably mounted in parallel relation in said frame, worm screws rotatably mounted in said frame and having threaded connection with said blades, and means for operating said screws to move said blades but maintaining 90 their parallel relation.

5. A device for creasing cardboard, cover-stock and the like, consisting of a frame adapted to be secured to a press, a bar mounted across the center of said frame, 95 two pairs of worm screws rotatably mounted in said frame and said bar, two creasing blades mounted in said frame and having threaded connection with said screws, and means for rotating said screws to position 100 said blades.

6. A device for creasing cardboard, cover-stock and the like, consisting of a frame adapted to be secured to a press, a bar mounted across the center of said frame, 105 two pairs of worm screws rotatably mounted in said frame and said bar, two creasing blades mounted in said frame and having threaded connection with said screws, and means for rotating said screws to position 110 said blades independently of each other.

7. A device for creasing cardboard, cover-stock and the like, consisting of a frame adapted to be secured to a press, a bar mounted across the center of said frame, 115 two pairs of worm screws rotatably mounted in said frame and said bar, two creasing blades mounted in said frame and having threaded connection with said screws, means for rotating said screws to position said 120 blades and means for locking said screws and blades in adjusted position.

8. A device for creasing cardboard, cover-stock and the like, consisting of a frame adapted to be secured to a press, a bar 125 mounted across the center of said frame, two pairs of worm screws rotatably mounted in said frame and said bar, two creasing

blades mounted in said frame and having threaded connection with said screws, and means for rotating said screws to position said blades independently of each other, and 5 means for locking each of said blades in its adjusted positions.

9. A device for creasing cardboard, cover-
stock and the like, consisting of a frame
adapted to be secured to a press, a bar
10 mounted across the center of said frame,
two pairs of worm screws rotatably mounted
in said frame and said bar, two creasing
blades mounted in said frame and having
threaded connection with said screws, a
15 scale attached to one of said creasing blades

and extending beyond the other blade, means
for rotating said screws to position said
blades independently of each other, and
means for locking each of said blades in its
adjusted positions.

10. A female die member for creasing
cardboard, coverstock and the like, comprising
a hooked end member adapted to en-
gage over the edge of a plate, two spaced
strips attached to said end member, and a 25
second end member provided with clamp-
ing means.

Signed by me, this 22nd day of August,
1919.

HERBERT O. TIBBITTS.
